CLAIM

We claim the ornamental design for a fireproof bag, substantially as shown and described.

DESCRIPTION

FIG. 1 is a top, perspective view of the fireproof bag, showing our new design;

FIG. 2 is a front elevation view thereof;

FIG. 3 is a side elevation view thereof;

FIG. 4 is a side elevation view thereof;

FIG. 5 is a rear elevation view thereof;

FIG. 6 is a top view thereof;

FIG. 7 is a bottom view thereof; and,

FIG. 8 is a perspective view thereof.

The broken lines show portions of the fireproof bag that form no part of the claimed design.

1 Claim, 8 Drawing Sheets
